UNITED STATES PATENT OFFICE.

HENRY COLOMB, OF TAVANNES, CANTON DE BERNE, SWITZERLAND.

APPARATUS FOR FINISHING JEWEL SETTINGS.

Application filed September 28, 1921. Serial No. 503,994.

To all whom it may concern:

Be it known that I, HENRY COLOMB, a citizen of the Swiss Republic, residing at Tavannes, Canton de Berne, Switzerland, ⁵ have invented new and useful Improvements in Apparatus for Finishing Jewel Settings, of which the following is a specification.

This invention relates to the construction of parts for time keeping machinery and ¹⁰ has for its main object the provision of settings containing drilled bearing jewels such that the cylindrical surface of the setting when reduced to size is exactly concentric with the drilled hole of the jewel. Further ¹⁵ objects of this invention are to provide apparatus for producing said settings, and to simplify the mechanism so that finished parts can be turned out accurately and rapidly without special care on the part of the ²⁰ workman.

A preferred embodiment of the invention is illustrated in the accompanying drawings, in which similar reference characters designate corresponding parts in all views, and ²⁵ in which:

Figure 1 is a section taken approximately on the center line through the essential parts of the mechanism, showing the relation of the parts at the commencement of the ³⁰ operation;

Figures 2 and 3 show the relative positions of the same parts at intermediate stages of the operation; and

Figure 4 shows the same parts at the completion of the operation.

Referring to these drawings, the mechanism comprises a die 1, having a base portion 1', each pierced by concentric cylindrical passages 2, 6 respectively, preferably ⁴⁰ of the same diameter, a transverse evacuation passage 5 separating the die proper 1 from the base portion 1'.

Suitably mounted for cooperation with the die 1 is a punch 7, adapted to be advanced into the die in the usual manner. Slidably mounted in the hole 6 of the base portion 1' is a cylindrical guide member 3, adapted to slide upwardly through the die opening 2 at least to the top thereof and ⁵⁰ downwardly below the evacuation passage 5, this guide member 3 having a projecting pin 4, preferably conical in shape, located centrally with respect to the guide member and consequently also located centrally with ⁵⁵ respect to the die opening 2. The evacuation passage 5 is arranged to convey a con-

tinuous stream of air beneath the die member 1, to receive and carry out from beneath the opening 2 finished work forced down by the punch 7. ⁶⁰

The work comprises a jewel setting 8 which in the rough is of slightly larger diameter than the die opening 2, in which is mounted a jewel 9, having an approximately central drilled bearing hole. ⁶⁵

The object is to line up a piece of work so as to bring the opening of the jewel concentric with the die for cutting the setting to size, then force the work through the die, and remove it. ⁷⁰

By the use of the apparatus described this is accomplished by raising the punch 7 out of the way, raising the guide member 3 to expose the pin 4 above the die 1, fitting a work piece in place with the hole of the jewel fitting on the pin 4, and lowering the punch to force the work into the die, at the same time pushing the guide member down, so that the pin 4 causes the work when forced into the die to be in such position that the ⁷⁵ cylindrical surface of the setting is concentric with the pin 4 and hence with the center of the hole of the jewel. After the work has been started properly into the die as shown in Figure 2, the guide member ⁸⁰ 3 is withdrawn as shown in Figure 3, and the punch 7 advanced to the position shown in Figure 4, completing and ejecting the work into the passage 5 where the air current as indicated by the arrow carries it off. ⁸⁵

By thus forcing the setting through the die 1, the latter shears off the peripheral surface of the setting, thereby removing any unevenness and rendering the setting truly cylindrical. ⁹⁰

Having now described my invention, I claim and desire to secure by Letters Patent:

1. Means for finishing settings for bearings for time keeping mechanism, comprising a die, a guide member slidably disposed therein and having a centrally disposed portion adapted to engage the hole of the jewel of the bearing, and a punch for cooperation with said die. ¹⁰⁰

2. Means for finishing settings for bearings for time keeping mechanism, comprising a die, a guide member slidably disposed therein and having a centrally disposed portion adapted to engage the hole of the jewel of the bearing, a punch for cooperation with said die, said punch being adapted to be advanced in the die to force the setting into ¹⁰⁵ ¹¹⁰

the die while still engaged by the guide member, and the guide member being adapted to be withdrawn to permit further advancement of the punch to completely finish and eject the setting.

3. Means for finishing settings for bearings for time keeping mechanism, comprising a die, a transverse evacuation passage therethrough, a guide member having centrally located means for engaging the hole of a jewel of a bearing slidably disposed in said die for movement to expose said engaging means above the die and for withdrawal below said evacuation passage, and 15 a punch for cooperation with said die.

4. Means for finishing settings for bearings for time keeping mechanism, comprising a die, a transverse evacuation passage therethrough, a guide member having centrally located means for engaging the hole 20 of a jewel of a bearing slidably disposed in said die for movement to expose said engaging means above the die and for withdrawal below said evacuation passage, a punch for cooperation with said die, and 25 means for sending a stream of air through said evacuation passage.

In testimony whereof I have signed my name to this specification.

HENRY COLOMB.
